CALF-DELIVERY APPARATUS

John Kuylen, Cleveland, Wis., assignor of one-half to Israel Axel, Cleveland, Wis.

Application March 29, 1939, Serial No. 264,740

2 Claims. (Cl. 128—352)

This invention appertains to animal husbandry, and more particularly to a novel device for facilitating the delivery of animals at birth.

5 One of the primary objects of my invention is to provide a calf-delivery apparatus which is of a light and compact form, and which can be easily and quickly operated.

Another salient object of my invention is to 10 provide a calf-delivery apparatus embodying an open frame having a sliding gate at one end for engaging the cow, and means at the other end for actuating a calf pull cable step by step.

A still further object of my invention is to 15 provide a calf-delivery apparatus of the above character, which will be durable and efficient in use, one that will be simple and easy to manufacture, and one which can be placed upon the market at a reasonable cost.

20 With these and other objects in view, the invention consists in the novel construction, arrangement, and formation of parts, as will be hereinafter more specifically described, claimed, and illustrated in the accompanying drawing, in 25 which drawing:

Figure 1 is a top plan view of my apparatus, with parts thereof broken away and in section to illustrate structural details.

Figure 2 is a side elevational view of my de- 30 vice.

Figure 3 is an end elevational view of my de- 35 vice, with parts thereof broken away and in section.

Figure 4 is a rear elevational view of my de- 40 vice, with parts thereof broken away and in section.

Figure 5 is an enlarged, detail, sectional view 45 taken on the line 5—5 of Figure 1, looking in the direction of the arrows, illustrating part of the cable drum-actuating means.

Figure 6 is an enlarged, longitudinal sectional view through one of the operating levers for the cable drum.

50 Referring to the drawing in detail, wherein similar reference characters designate corresponding parts throughout the several views, the letter A generally indicates my novel calf-delivery apparatus, and the same embodies an elongated open frame, which may consist of a pair of upper longitudinally extending beams 10 and 11 and a pair of lower, spaced, parallel, longitudinally extending beams 12 and 13. These beams can be made of any preferred material, but, as illustrated, the same consist of hollow tubing 55 for the sake of lightness and strength.

The beams can be of a telescopic nature, whereby the active length of the frame can be changed to suit varying conditions, and the telescopic sections of the beams can be held in an adjusted position by means of bolts 14, which can pass through openings in said sections. The lower beams 12 and 13 at the front of the device are connected by a channel beam 15, and this channel beam has welded or otherwise secured thereto, upright channel beams 16, which are, in turn, secured to the beams 12 and 13, and to the upper beams 10 and 11.

In order to facilitate the connection of the beams 10, 11, 12, and 13 with the channel beams, 15 the front ends of the tubular beams can have fitted therein brackets or feet 16', as is clearly shown in Figures 1 and 2. These feet 16' can then be welded or riveted to the channel beams.

The arrangement of the channel beams is such 20 that a front open framework is provided, and the channel beams 16 receive a transversely extending, lower block 17 and a similar upper block 18. The blocks 17 and 18 are preferably formed from wood, and their adjacent edges are notched so as 25 to form a delivery opening 19 for the calf. The upper block 18 can raise and lower in the channel beams 16, and, hence, the active size of the opening 19 varies, and the block 18 can rise and fall as a calf passes through the opening.

The rear end of the apparatus is also provided 30 with an open rectangular frame 20, which can be formed from channel iron. The rear ends of the longitudinal beams have secured therein feet or brackets 21, which can be riveted or welded 35 to the frame 20.

The rear frame 20 supports a transversely extending drum 22, and this drum is rotatably mounted on a shaft 23, the opposite ends of which can be mounted in bearing brackets 24. The bearing brackets 24 can be welded or otherwise secured to the rectangular frame 20. The drum 22 is adapted to have wound thereon a pull cable 25, and this cable is adapted to extend longitudinally of the frame and through the opening 19, 45 and is adapted to be firmly secured to the calf being delivered.

The drum is preferably rotated in a step by step movement, and, hence, the opposite ends thereof are provided with ratchet teeth 26. 50 Rockably mounted on the shaft 23 at the opposite ends of the drum 22 are operating levers 27, and these levers carry spring-pressed dogs 28, which are adapted to engage the ratchet teeth 26. Thus, by working the levers back and forth, 55

the drum can be rotated and the cable will be wound thereon.

In order to permit the quick paying off of the cable from the drum, means is provided for holding the dogs 29 entirely out of engagement with the ratchet teeth 26. This means can consist of a rod 30 slidably mounted in each operating lever. The outer ends of the rods 30 are provided with finger-actuating knobs 31, and these knobs are connected to the rods by cross-pins 32. The cross-pins 32 extend through slots 33 formed in the levers 21.

Obviously, by pushing down on the knobs, the rods 30 can be forced inwardly. The inner ends 15 of the rods 30 are of a V-shape, and are adapted to engage the inclined walls of V-shaped notches 34 formed in the yokes 29. Thus, when the rods 30 are forced down, the same will ride on the inclined walls of the notches and force the dogs 20 inwardly.

In use of my apparatus, the front of the device is placed so that the blocks 17 and 18 will firmly engage the cow, and the cable 25, as stated, is brought through the opening 19 and made fast 25 to the calf. The drum 22 is then operated so as to actuate the cable in a step by step movement.

Changes in details may be made without departing from the spirit or the scope of my invention, but what I claim as new is:

30 1. A calf-delivery apparatus comprising, an

elongated frame, a pair of blocks at the forward end of the frame for engaging a cow, the meeting edges of said blocks being notched to form an opening, one of said blocks being movable relative to the other whereby to vary the size of the opening, a pull cable for the calf passing through said opening, a drum for winding up the cable, means for rotating the drum including operating levers at the opposite ends of the drum mounted for rocking movement, ratchet teeth on 10 the ends of the drum, spring-pressed dogs on the levers for engaging said teeth having inclined faces, and rods slidably mounted on said levers having inclined ends for engaging said faces for holding and forcing the dogs out of engagement with the teeth for releasing the cable upon inward movement of the rods on said levers. 5

2. A calf-delivery apparatus comprising, a pair of spaced, parallel, longitudinally extending, top beams and a pair of spaced, parallel, longitudinally extending bottom beams, open rectangular frames connecting the front and rear ends of the beams together, the front open frame being formed from channel iron, blocks slidably mounted in the channel iron extending transversely of the apparatus and having notches in their meeting edges to define an opening, a drum rotatably mounted on the rear frame, a pull cable for the calf adapted to be wound upon the drum, and means for rotating the drum. 15 20 25 30

JOHN KUYLEN.
